SLIDING DOORS

Friedrich Wilhelm Kiekert, Heiligenhaus, Germany

Application October 24, 1950, Serial No. 191,831

Claims priority, application Germany October 31, 1949

14 Claims. (Cl. 20—24)

This invention relates to sliding doors and more particularly relates to a sliding door suitable for vehicles which in its closed position is flush with the outer wall of the vehicle and from which it must first be moved away or lifted whereupon the door can then be displaced in a lateral direction parallel to the wall of the vehicle.

It is an object of the present invention to provide an improved sliding door which avoids the disadvantages of previously known sliding doors.

Another object of the invention is to provide an improved sliding door which does not require guiding or supporting means for the door which project beyond the wall of the vehicle when the door is lifted or moved.

A further object of the invention is to provide a sliding door which combines great safety with small maintenance costs, which has a simple construction of pleasant form and which does not require special openings or other discontinuities in the construction or frame work of the vehicle.

The door of the invention is supported by or suspended from a rod by means of a lever arrangement having one or two arms, the supporting rod being movably arranged on rollers and slidable with the door. The supporting rod serves as a swivel or bearing shaft for the lever arrangement. The lifting of the door, that is, its movement out of the plane of the vehicle wall is effected by tilting the lever arrangement. This lever in turn is tilted by guiding one of its arms by rollers in a suitably curved rail or channel-shaped guiding member. These suspension, guiding and tilting members may be located in the upper portion of the door only or in both the upper and lower door portions. It is also feasible to utilize several lever arrangements instead of one. It has been found that the operation of the sliding door of the invention may be further improved by replacing the lever arrangements having two arms with single-arm supporting levers disposed in the upper and lower door portions which are adapted to tilt in opposite directions and toward each other. In this case it is also feasible to secure the guiding rollers, which effect a rotation of the supporting rods, directly on the supporting levers.

By arranging the supporting levers in this manner the transmission of the force to the tiltable guiding members of the door is more favorable whereby the force required to actuate the door is considerably reduced. Furthermore, the guide members of the sliding door can be disposed in a very small space in the interior of the vehicle and require few additional parts.

A particularly favorable arrangement which makes it possible to provide a step-like entrance to the vehicle is obtained when the supporting lever acting on the lower half of the door is linked to an arm rigidly connected to the door. By suitable choice of the length and height of this intermediate member or arm it is possible to provide any desired relation or dimension of the entrance steps.

It has been found suitable particularly if the sliding door has two leaves, to connect the supporting lever or its hub with tubes which, in turn, are guided by rollers

2

moving along fixed supporting rods. The tubes serve essentially the purpose to secure the supporting levers and to support the door leaves suspended from the levers along as long a distance as desired by means of the supporting rollers moving over the supporting rod. Consequently, the door is not subject to undesirable vibrations in its open position or in any intermediate position.

It has been found that sliding doors of the construction hereinabove described, can be lifted out of the vehicle wall and opened easily from the outside without encountering any appreciable resistance, while the opening of the door from the interior of the vehicle requires a larger amount of force. This is caused by the fact that when the door is opened from the outside, a component or a vector of the force is effective in the direction of the movement of the door out of the vehicle wall plane, while when the door is actuated from the interior of the vehicle, this component is in a direction opposite to the intended movement of the door.

20 In order to improve this operating condition the door is provided, in accordance with the invention, with means which make lifting and opening of the door from the exterior of the vehicle as easy as from the interior, even if the door has a considerable weight.

25 To this end an additional arrangement is provided which first unlocks the door and thereafter initiates lifting thereof from the plane of the vehicle. This arrangement includes essentially a pressure rod disposed parallel to the vertical door edge which is lifted by the inner door handle arranged to be tilted. Since the upper end of this pressure rod is connected with the lower end of the supporting lever which effects the lifting and tilting of the door, the door is lifted a small distance from the plane of the vehicle wall when the pressure rod is lifted.

30 When the door is moved laterally, further lifting of the door is effected by the slide rail which is disposed in the interior of the vehicle and which cooperates with the supporting lever.

It is also essential that the pressure rod which has the above described function also serves the purpose to unlock the door. To this end a lever arrangement which preferably is disposed horizontally at the height of the door bolt is connected to the pressure rod by means of an angle lever or the like. When the pressure rod is lifted by actuating or tilting the inner door handle, the lever which actuates the door bolt and which is connected to the pressure rod, tilts in such a manner that the bolt is removed and the door is unlocked. A further lifting of the pressure rod by the inner door handle initiates the tilting movement of the supporting lever from which the door is suspended and therefore the lifting of the door away from the vehicle plane. This movement is easily effected by actuating the inner door handle by means of the pressure rod; the further displacement of the door can then be effected just as easily.

55 The sliding door of the invention will be explained, by way of example, by means of several embodiments of the invention illustrated in the accompanying drawings, in which:

60 Fig. 1 is a front view of a sliding door in accordance with the invention as viewed from the interior of the vehicle having supporting levers with two arms;

Fig. 2 is a side view, partly in section, of the door of Fig. 1;

65 Fig. 3 is a side view, partly in section and on enlarged scale, of the upper portion of the door of Fig. 1 with its suspension and guide means;

Figs. 4 and 5 illustrate a modification of the door of Fig. 1 which is suspended by a pair of supporting levers as viewed from the interior of the vehicle, Fig. 4 showing the closed position and Fig. 5 the open position of the door;

Fig. 6 is a side view, partly in section and on enlarged scale, of another modification of the suspension and actuating members illustrated in the closed and opened position of the door;

Fig. 7 is a front view, as viewed from the interior of the vehicle, of a door having one lead and supporting levers with single arms disposed to face each other;

Fig. 8 is a plan view of the door of Fig. 7;

Fig. 9 is a side view of the door of Fig. 7;

Fig. 10 is a front view of a door having two leaves as viewed from the interior of the vehicle;

Fig. 11 is a plan view of the door of Fig. 10;

Fig. 12 is a side view of the door of Fig. 10, partly in section;

Fig. 13 is a sectional view on enlarged scale illustrating the upper suspension mechanism of the door of Fig. 10;

Fig. 14 is a front view of the unlocking and lifting arrangement of a sliding door in accordance with the invention with the door panel removed;

Fig. 15 is a plan view of the door of Fig. 14, with parts broken away, the inner door handle being illustrated in different operating positions; and

Fig. 16 is a side view of the lifting arrangement of the door in accordance with Fig. 14.

Referring now to the drawings, and particularly to Figs. 1, 2 and 3, the door 1 which is to be displaced laterally with respect to the outer wall 2 of the vehicle is flush with the vehicle wall 2 in its closed position. In accordance with the invention the door is suspended from a rod 3 disposed at a short distance from and above its upper edge which, together with the door, is guided in the interior of the vehicle (Figs. 1 to 3) by guide means consisting of rollers 4. This rod 3 serves as tilting axis for a two-arm lever supporting arrangement 5 secured to rod 3. The door is movably mounted on one of the lever arms 6 while the other lever arm 7 is guided by rollers 9 moving in a rail 8 arranged in the interior of the vehicle so that when the door is removed from or out of the plane of the vehicle wall, the lever supporting arrangement 5, 6, 7 can be rigidly connected with the rod or tube which latter is then rotated in its guide means 4 when the door is removed. It is, of course, also feasible to provide a supporting rod having other cross-sectional shapes in which case the lever supporting arrangement 5, 6, 7 may be tilted about the rod.

Such a construction is illustrated in Figs. 4 and 5 wherein the supporting lever arms 6 of the supporting lever arrangement are connected to one side of the supporting rod 3 and are shaped as an arc or bow so that they can pass between the rollers 4 without obstructing the same. The other lever arm 7 which effects tilting of the supporting lever arrangement is also disposed on one side of the rollers 4, as is the suitably bent or curved guide rail 8. This construction of the supporting lever arrangement has the further advantage that the supporting rod 3 may be made comparatively short and that any desired number of rollers 4 may be provided therefor. In Figs. 4 and 5 the movement of the supporting lever arms 5, 6, 7 is shown from the closed position into the position of the door when it is lifted from the vehicle plane.

Another type of suspension for the door is illustrated in Fig. 6. Here the door, instead of being suspended from a rod 3 slidable together with the door, is suspended from a sliding member 10 and is guided by rollers 11 in a rail 12. The supporting lever arrangement 6, 7 is tiltably supported on a bolt 13 forming a part of or secured to sliding member 10. The displacement or the tilting of the door from the closed to the open position is again effected by the guide rail 8 the rollers 9 provided at the free end of lever arm 7 being omitted. It is also feasible to tilt the lever 6, 7 in order to lift the door by connecting it rigidly with the sliding member 10 which runs in the rail 12 and by rotating this sliding member together with its rail.

Finally it is also possible to arrange the supporting and tilting lever 6, 7 as single-arm lever which is then tilted by a guiding means or against a stop which acts directly on the lever arrangement 6, thereby causing the supporting arrangement and the door to move into the lifted position.

Several embodiments of a sliding door provided with a one arm lever are shown in Figs. 7 to 14. In the embodiment of Figs. 7 to 9 the upper part of the door is swingably connected by bolt 13a with the supporting lever 14 which, in turn, is secured to the supporting rod 3 and may be displaced, together with the rod by means of pairs of rollers 4. In recess 15 of the lever arm 14 a rotatable guide roller 16 is provided which cooperates with the channel-shaped rail 8, the end of which is bent off at a small angle.

A supporting arm 17 is secured to the lower portion of the door and in the free end of the same the other supporting lever 18 is journalled in such a manner that the tilting arms of the supporting levers 14 and 18 are directed toward each other. The residual supporting and guiding means of the lower door portion are identical with the corresponding parts of the upper door portion.

The just described and illustrated arrangement of the supporting levers 14 and 18 makes it possible to save considerable space. It is also possible to provide in a very simple manner steps 19 and 20 for entering the vehicle. The space indicated by arrow 21 may be covered by a protecting sheet (not shown) when the door is closed, and this sheet may be displaced together with the supporting arm 17.

The door operates in the same manner as the door shown in Figs. 1 to 6 and previously described. When the door 1 is opened, the rollers 16 move against the inclined portion of the rail 8 and both supporting levers 14 and 18 tilt to bring the door into the position shown by the dash lines where it is lifted away from the plane of the vehicle 2. Thereafter the door which is suspended from the supporting rods 3 may be displaced laterally along the rollers 4. When the door is closed, the just described movement takes place in the opposite direction.

Figs. 10 to 13 illustrate a sliding door having two wings 22 and 23. The general construction is essentially the same as shown in Figs. 7 to 9. Also in this case supporting levers 14 and 18 are provided in the upper and lower portion of each door wing, the levers having tilting arms which are disposed to face each other. In accordance with the invention the hubs of the supporting levers are rigidly secured to tubes 24 which are connected with roller housings 25 so as to transmit power. The rollers disposed in these housings roll along the outer surface of supporting rods 26 which are rigidly connected to the wall of the vehicle or the like and which may, for example, consist of tubes. Suitably an annular free space 27 is provided between the supporting rods 26 and the tubes 24 so that, when the door is displaced, only rolling friction is present.

When the door wing 22 and 23 are opened or displaced, the supporting levers 14, 18 tilt the door into the position shown in dot and dash lines. The tilting movement of the supporting levers is transmitted by means of tubes 24 to the roller housings 25 which then tilt about the supporting rods 26 into the position shown in dot and dash lines. In this position the door wings 22 and 23 may readily be displaced laterally along the supporting rods.

Figs. 14 to 16 illustrate an unlocking and lifting arrangement in accordance with the invention which makes it possible to lift the vehicle door from the inside of the vehicle from its closed position out of the plane of the vehicle wall without exerting any appreciable force. As shown in Figs. 14 and 15 the door handle 29 which is disposed in the inside of the vehicle may be tilted about its pin 28. The cam or stud 30 of handle 29 cooperates with one leg of a lever 31 which, in turn,

acts upon a pressure rod 33 arranged parallel to the vertical door edge. The upper end 38 of the pressure rod 33 is rotatably connected with the lower end of the supporting lever 14 which is disposed in the interior of the vehicle. The supporting lever 14 is the essential part of the lifting device because it is supported by the rod 3 disposed between the rollers 4 and is journalled to the door at 13a. When the supporting lever 14 together with the rod 3 is tilted in the direction of the arrow in Fig. 16, the door is lifted entirely away from the plane of the vehicle. This tilting of the rod 3 is effected by a suitably positioned channel-shape rail 8 cooperating with the rollers 16 arranged on the supporting lever 14. Shortly after the opening movement of the door is initiated by lifting the pressure rod 33, an additional force acts on the supporting lever 14 and consequently an appreciable reduction of the necessary force is obtained just at the beginning of the opening movement of the door from the interior.

Unlocking of the door by the inner door handle 29 is effected through rod 35 disposed at the height of the door lock bolt 34. The rod 35 is connected through an angle lever 36 or the like to the pressure rod 33 because the other end of the angle lever engages a bolt 37 on the rod 33.

When the inner door handle is first tilted, the lifting device or pressure rod 33 effects at first the withdrawal of the lock bolt 34; upon further tilting of the door handle tilting of the lever 14 is effected, from which the door is suspended. It has been found that in this manner very heavy doors can be easily moved from the wall of the vehicle with which they are flush in their closed position and then displaced laterally as conventional sliding doors. It is also important that regardless of whether the door is opened from the inside or from the outside, the force required remains the same.

The sliding door of the present invention is suitable for vehicles and particularly for railway cars. It solves the problem with the simplest means which are particularly adapted to its purpose of lifting a sliding door which is normally flush with the plane of the vehicle wall and of displacing the door laterally parallel to the wall of the vehicle from the inside or outside of the vehicle without the necessity of disposing any means which effect movement of the door outside of the vehicle. In contradistinction to the known devices of this type it is possible to lift the sliding door of the invention only so much before its lateral displacement commences as this is required by the parts of the door, such as the door handle; this is made possible by the particular arrangement of the suspension and displacement means of the sliding door in conformity with the invention.

This invention has been described with reference to a preferred embodiment and it will be understood that many variations and modifications thereof may be resorted to without departure from the scope of the invention as defined in the following claims.

What I claim is:

1. In a slidable door structure for wall enclosed vehicles, where in the closed position the door is flush with a vehicle wall, a combination of means for the advance of the door from the vehicle and for the lateral displacement of the advanced door alongside said wall, said means comprising a longitudinal horizontal member for the suspension of the door, said suspension member being displaceably supported inside of said vehicle and extending in the longitudinal direction thereof, rollers fixed in said vehicle for the support of said displaceable suspension member, at least one lever mechanism rotatably supported on said suspension member, said door being suspended from the lower end of said lever mechanism, a cavity enclosing guide rail for said lever mechanism located in the interior of said vehicle and extending parallel with said suspension member.

2. In a slidable door structure according to claim 1,

the upper end of the vertical lever mechanism extending into the inner cavity of the guide rail.

3. In a slidable door structure according to claim 1, the upper end of the vertical lever mechanism extending into the inner cavity of the guide rail and being provided with a roller.

4. In a slidable door structure according to claim 1, two sets of means for the advance of the door from the vehicle and for the lateral displacement thereof along said vehicle, said means being located in the vicinity of the upper and of the lower edge of said door.

5. In a slidable door structure for wall enclosed vehicles, where in the closed portion the door is flush with a vertical wall, a combination of means for the advance of the door from its vertical closure position and for its lateral displacement alongside said wall, said means comprising a horizontal rod for the suspension of the door, said suspension rod being supported inside of said vehicle and extending in the longitudinal direction thereof, rollers fixed in said vehicle for the support and the displacement of said suspension rod, a double arm lever composed of a lower and an upper arm rotatably supported on said suspension rod, said lower lever arm being rotatably connected to the upper edge portion of said door, a guide rail located in the interior of said vehicle and extending parallel with and above said suspension rod, the upper lever arm extending into said guide rail, said suspension rod serving as a tilting axis for said double arm lever.

6. In a slidable door for vehicles which in its closure position is flush with the vehicle wall, means for the outward lifting of said door from its closure position for a displacement along the outside of said wall and its return into said closure position, said means comprising a member for the suspension of the door, said member being located in the interior of the vehicle, means to enable a displacement of said suspension member in the longitudinal direction of the vehicle, a leverage rotatably supported by said suspension member and hingedly connected at its lower end with the upper edge portion of said door, a roller applied to said leverage and a guide rail located in the vehicle for the guidance of said roller said guide rail being provided with a curved bend at one end to outwardly swing said leverage, whereby the door suspended from said leverage upon its lift from the vehicle may be displaced parallel with and alongside said vehicle wall.

7. In a slidable door structure according to claim 6, the door suspension member comprising a guide rail mounted in the inside of the vehicle, two spaced rollers located in said rail in a superposed position and a guide block rotatably connected to the leverage system and slidably supported by said rollers.

8. In a slidable door structure according to claim 6, a handle attached to the inside of the door, a vertical rod vertically displaceably located at the edge of the door, the upper end of said rod being hingedly connected to the lower end of the leverage mechanism, and means inserted between said handle and said vertical rod to effect the vertical displacement of the latter.

9. In a slidable door for vehicles, which door in its closure position is flush with the vehicle wall and is provided with a swingable leverage of which one end is hingedly connected with the upper door end, means for supporting and guiding said leverage permitting its displacement parallel to the vehicle wall, said means being located inside of the vehicle in such a manner as to permit the door carried by said swingable leverage to be outwardly lifted from the vehicle wall and to be displaced parallel to the outer wall face by the displacement of said swingable leverage, a rail located inside said vehicle substantially parallel to said supporting and guiding means and being provided with a curved bend at one end to outwardly swing said leverage, a roller rotatably connected with said swingable leverage and coacting with

said guide rail to tilt said leverage during its parallel displacement alongside the vehicle wall whereby in forcing said door in the opening direction said leverage connected with said door is tilted by means of said roller in such a manner that the door is lifted in an outside direction and moved parallel to said wall into its open position and by forcing said door in the opposite direction said door is returned and relowered into its closed position.

10. In a slidable door arrangement according to claim 6 the means for the outside lift of the door from its closure position and its displacement along the outside of the vehicle wall being applied to the upper and lower inner end portion of the door and to the vehicle.

11. In a slidable door arrangement according to claim 6 said longitudinal door suspension member having a tubular shape and pairs of rollers to support said suspension member therebetween for its longitudinal displacement and its rotation.

12. In a slidable door arrangement for vehicles according to claim 6 the said suspension member being at its upper end connected with a tube, a stationary rod to displaceably and rotatably support said tube and rollers to effect said displacement and said rotation.

13. In a slidable door arrangement for vehicles ac-

ording to claim 6 the roller being attached by means of a lever to the top end of said leverage and above the same.

14. In a slidable door arrangement for vehicles according to claim 6 the roller being directly connected to said 5 leverage.
